WALL BRACKET FOR A TELEPHONE HANDSET OR SIMILAR ARTICLE

Frank Dellaguardia, 33834 Jefferson,
St. Clair Shores, Mich.

Filed Apr. 19, 1960, Ser. No. 60,245

Term of patent 14 years

(Cl. D26—14)

FIG. 1 is a perspective view of the wall bracket for a telephone handset or similar article, embodying my novel design.

FIG. 2 is a front elevation of the same.

FIG. 3 is a side elevation of the same the opposite side being substantially a mirror image thereof.

I claim:

The ornamental design for a wall bracket for a telephone handset or similar article, as shown and described.
